LOOM BEAM SUPPORT BRACKET

William N. Conway, North Grafton, Mass., assignor to
Draper Corporation, Hopedale, Mass., a corporation of
Maine

Filed May 13, 1964, Ser. No. 79,959

Term of patent 14 years

(Cl. D92—15)

FIG. 1.

FIG. 5.

FIGURE 1 is a top plan view of a loom beam support bracket showing my new design;

FIGURE 2 is a front elevational view thereof;

FIGURE 3 is a left end elevational view thereof;

FIGURE 4 is a right end elevational view thereof;

FIGURE 5 is a bottom plan view thereof;

FIGURE 6 is a rear elevational view thereof;

FIGURE 7 is a front perspective view thereof;

FIGURE 8 is a rear perspective view thereof.

I claim:

The ornamental design for a loom beam support bracket, substantially as shown.
